PUMP JACK

Wilford P. Heffernan, Humble, Tex., assignor of
one-fourth to Charles G. Eidson, Houston, Tex.

Application April 20, 1937, Serial No. 138,013

7 Claims. (Cl. 74—103)

The present invention is a power pump jack, used, among other purposes, particularly in oil fields for transmitting power from a source to a reciprocating pump for raising and lowering the plunger thereof.

A great variety of pump jacks of this type have been employed but, so far as is known, none have been devised for applying a true vertically straight line motion to the plunger of the pump, which motion is essential and necessary to prevent wear, inefficient and uneconomical operation. The pump rod or piston rod extending into the well should always be lifted vertically to prevent whipping, wear on the stuffing box and unnecessary strain on the moving parts.

The principal object of this invention is the provision of a pump jack having a construction which will apply a truly vertically straight line motion to the pump rod from a remote source, such as a substantially horizontal pulling cable, to vertically lift the pump plunger in the well by means of a pump rod which extends outwardly from the well.

Another object of the invention is the provision of a pump jack of the above stated character which has novel features of construction enabling adjustment of the jack to increase or diminish the stroke of the pump plunger without disassembling any of the parts of the jack or from the plunger.

Another object of the invention is the provision of a pump jack having means which will permit adjustment of the parts of the jack while in operation for increasing or diminishing the power of the stroke and without disconnecting the jack from its source of power or from the pump.

Another object of the invention is the provision of a pump jack assembled in a self-contained unit ready to be set over a well and anchored thereto.

A further object of the invention is the provision of a pump jack having a construction permitting it to be serviced without moving the jack from its position, thus saving much time and labor.

With the above and other objects in view as will appear as the specification proceeds, the invention further resides in the sundry details of construction, combination and arrangement of parts hereinafter more fully described and pointed out in the appended claims.

In the drawings which show the preferred embodiment of the invention as at present devised:—

Fig. 1 is a side elevation of the jack positioned

in place and connected with an oil pump, the pump and its connection to the jack being shown in dotted lines;

Fig. 2 is a top plan view of the jack shown in Fig. 1;

Fig. 3 is a detail sectional view taken substantially on line 3—3 of Fig. 1;

Fig. 4 is a similar view to Fig. 1 but showing a slightly modified form of the jack;

Fig. 5 is a front end view of the jack as shown in Figs. 1 and 4; and

Fig. 6 is a transverse sectional detail view taken substantially on line 6—6 of Fig. 1.

Referring in detail to the drawings in which like characters refer to similar and like parts throughout the several views, 10 denotes a suitable base for the jack, which base may comprise spaced longitudinal members *a* and *b* connected together by transverse cross members *c* and *d* of such number and construction as may be necessary or desired.

Suitably mounted and secured to the base 10, at a medial portion thereof, are a pair of spaced tubular guides 11; and preferably as shown in the drawings, guides are mounted on said members *a* and *b* respectively of the base 10 and arranged in transverse alignment. These guides 11 may be suitably braced to the base, as shown, by rods 12 and 13 and at their upper end portions by a transverse rod 14 which latter connects the two guides 11.

A pair of guide rods 15 are slidably disposed in each of the tubular guides 11 respectively, and extend from the upper ends of the latter for a desired distance in their normal lowered position. The guide rods 15, preferably, have a sliding fit in the tubular guides 11 by providing a bearing collar 16 at the upper ends of the tubular guides 11 between the latter and the guide rods 15; and the guide rods 15 may be provided on their lower ends with a similar bearing

collar 16a having a piston-like fit with the interior walls of the tubular guides 11. The oil may be, and preferably is, contained in the lower ends of the tubular guides 11 to form a dash-pot or cushion for the guide rods and, further, for enabling self-lubrication of the surfaces of the guide and guide rods.

A pump lifting beam 17 is connected substantially intermediate its ends to the upper ends of the guide rods by any suitable means, such as the transverse connecting pin or rod 18 and is held in an inarticulate substantially horizontal position by means of equalizing brace rods 19 disposed on opposite sides of the beam and connected to the jack-rocker, generally indicated by

the numeral 20. A pitman rod 21 connects the beam 17 with the jack-rocker 20 for imparting lifting movement to the beam 17.

The brace rods 19 preferably extend from the rear end of the lifting beam 17, where they are pivoted as at 40, to the forward end of the jack-rocker 20, where they are pivoted as at 22. The pitman rod 21 is pivotally connected, as in bearing 23, to the forward end of the jack-rocker 20 and has its upper end similarly pivotally connected, as at 24, to the lifting beam 17, the pitman 21 being in a substantially vertical position as shown.

The jack-rocker 20 may take any particular form provided it has the function of a bell-crank-lever, but is here preferably disclosed as a right-angle-triangular frame having one leg *e* thereof forming a normally horizontal arm and its other leg *f* providing a normally vertical arm, while the member *g* provides a brace for the members *e* and *f* and is disposed substantially co-incident with the hypotenuse of the triangle. In actual construction the arm *e* is longer than the arm *f* and is disposed in a cradle 25 at its end portion adjacent the apex of the arms *e* and *f*. This cradle 25 is pivotally supported at its rear end on the base of the frame, such as by a suitable roller or bearing surface 26, disposed in a complementary bearing 27 provided on the end cross-piece *d*, as shown in Figures 1, 2, 3 and 5. The forward end of the cradle is provided with aligned openings 28 with which may be aligned openings 29 in the jack-rocker arm *e*, and thru which openings a fastening pin 30 is disposed for connecting the arm with the cradle. Thus, it will be seen that the position of the jack-rocker may be adjusted longitudinally in the cradle to vary its distance with respect to the pump *P*, to increase or decrease in a general manner the extent of lift of the beam 17 or to increase or decrease the leverage from the source of power to the lifting beam 17.

To permit a change in the leverage of the jack-rocker 20 for increasing and decreasing the amount of vertical lift of the beam 17, while the pump jack is in operation, and further to permit fine regulation of this adjustment, the lower line *L* (which is pulled to rock the jack-rocker 20 on its fulcrum 26 from a source not shown) is connected with the vertical arm *f* of the jack-rocker 20 and slidably, at will, by suitable means, such as a feed screw 31 rotatably mounted in the upper portion of the jack-rocker, as at 32, and which has a handle or other operating means 33 for rotating the screw. It is preferred to provide a slide block 34 thru which the feed screw 31 is threaded. The slide block 34 has a shoe 37 thereon slidably bearing against the vertical arm *f* of the jack-rocker, as shown particularly in Figs. 1 and 6. A stirrup 38 is loosely carried by the slide block 34 and is held in place by a removable pin 39, the stirrup 38 being detachably connected to the power pull line *L*.

It will thus be seen that whenever the line *L* is pulled by the usual power means (not shown) the jack-rocker 20 will fulcrum at 26 raising the beam 17 thru the pitman rod 21 but, by reason of its connection with the vertically movable guide rods 15 and with the equalizing bars 19 cooperating with the pitman rod 21, the beam maintains an inarticulate position, thus imparting a true vertical reciprocating movement to the connecting rod *r* of the pump *P*.

When it is desired to effect a general adjustment of the jack-rocker with respect to the

pump, this may be accomplished by moving the jack-rocker 20 in the cradle 25 thru the medium of the pin 30 in the openings 29 of the jack-rocker. This adjustment may, of course, vary the horizontal position of the beam 17 and, therefore, a corresponding adjustment of the equalizing brace rods 19 is effected at 40 by a selection of any one of the openings 19^a provided therein. Also, should it be desired to effect a change in the vertical lift of the beam, while the jack is in operation, this may be accomplished without dismantling the jack or discontinuing operation of the pump *P* by suitable vertical adjustment of the slide block 34 by operation of the adjusting screw 31. Variation in lift caused by the screw 31 does not require any re-adjustment of the equalizing bars 19, as above mentioned, in connection with adjustment in the cradle 25.

When it is desired to swing the pump rod connecting end *x* of the beam 17 clear of the well, the bolt 21 is removed disconnecting the equalizer rods 19, thus enabling the beam to be swung on the cross bar 18 in the dotted line position as shown in Fig. 1.

For some uses it may be desirable to eliminate the cradle 25 and the adjustment effected thereby. To this end there is shown in Fig. 4 a modified form of the invention, in which parts corresponding to like parts throughout the other views just described have the same numerals raised by the exponent *b* and the same letter characters raised by the exponent prime ('). Therefore, detail description of this modification need not be given in the interest of conserving space; but suffice it to say, that Fig. 4 is identical with the other views except that the arm *e'* of the jack-rocker 20^b is directly fulcrumed at its inner end portion by means of a roller 26^b or the like disposed in bearing 27^b and that the equalizing brace rods 19^b are not provided with a plurality of openings 19^a.

Having thus described the invention and the manner in which it is to be performed, it is to be understood that the invention is not to be restricted to the embodiments herein shown and described because it may take other forms and be modified in numerous respects which fall within the scope of the appended claims.

What is claimed is:

1. A pump-jack comprising a lifting beam mounted in vertical guides, a jack-rocker, a connection between the jack-rocker and the lifting beam for raising and lowering the latter, said jack-rocker comprising a bell-crank-lever one end of which is connected with the lifting beam and by which and said guides the lifting beam is solely supported, the other end portion of said lever being connectable to pull line.

2. A pump-jack comprising a lifting beam mounted in vertical guides, a jack-rocker including a bell-crank-lever one end of which is connected with the lifting beam and by which and said guides the lifting beam is solely supported, the other end portion of said lever being connectable to pull line, and means for adjusting the bell-crank-lever with respect to its point of connection with said lifting beam.

3. A pump-jack comprising a lifting beam mounted in vertical guides, a jack-rocker including a bell-crank-lever one end of which is connected with the lifting beam and the other end of which is connectable to a pull-line, means for adjusting the bell-crank-lever with respect to its point of connection with the lifting beam,

slidable member on the arm of the bell-crank-lever connectable to the source of power and to which slidable member said pull line is attachable, and a feed screw carried by the jack-rocker and threaded in said slidable member, whereby said slidable member may be adjusted along the length of said arm at will.

4. A pump-jack comprising a base, vertical guide means mounted on the base, a substantially horizontal lifting beam pivotally mounted in guide means, a jack-rocker including a bell-crank-lever fulcrumed on the base, a pitman rod connecting one end of the bell-crank-lever to the lifting beam at one side of the beam's connection to said guide means, equalizing brace rods connected to the beam on the other side of its connection to said guide means and to the said end portion of the bell-crank-lever, the other end of the bell-crank-lever being connectable to a source of linear power whereby the jack-rocker is actuated.

5. A pump-jack as set forth in claim 4 further characterized by the fulcrum of the bell-crank-lever comprising a cradle member in which the bell-crank-lever is longitudinally adjustably carried, and means for permitting adjustment of the equalizing brace rods to compensate for said ad-

justment of the jack rocker in said cradle member.

6. A pump-jack as set forth in claim 4 further characterized by the end of said bell-crank-lever connectable with a source of power having a sliding block mounted thereon to which a source of power is connectable, a feed screw mounted in said lever and threaded in said block, whereby the point of power connection with the bell-crank-lever may be adjusted at will along the length of said arm of the bell-crank-lever.

7. A pump-jack comprising a base, a pair of spaced vertical tubular guides mounted on the base, a guide rod in each of said tubular guides, respectively, a substantially horizontal lifting beam pivotally mounted on the ends of said guide rods intermediate its ends, a jack-rocker including a bell-crank-lever fulcrumed on the base, a pitman rod connecting one end of the bell-crank-lever to the lifting beam at the forward end portion of the latter, equalizing brace rods connecting the other end of the beam to said end portion of the bell-crank-lever, the other end of the bell-crank-lever being connectable to a source of linear power, whereby the jack-rocker is actuated.

WILFORD P. HEFFERNAN.
